(57) CLAIM

The ornamental design for a weatherproof electrical plug cover, as shown and described.

DESCRIPTION

FIG. 1 is a perspective view of a weatherproof electrical plug cover with the lids in a closed position;

FIG. 2 is another perspective view of the weatherproof electrical plug cover with the lids in an open position;

FIG. 3 is a front view of FIG. 2, wherein a rear view is a mirror image of the front view;

FIG. 4 is a left side view of FIG. 2;

FIG. 5 is a right side view of FIG. 2;

FIG. 6 is a top view of FIG. 2; and,

FIG. 7 is a bottom view of FIG. 2.
